United States Patent Office

Des. 175,660
Patented Sept. 20, 1955

175,660

HAND-OPERATED WATER PUMP

Harold George Welch, Southampton, England

Application December 1, 1953, Serial No. 27,862

Term of patent 7 years

(Cl. D65—1)

FIG. 1.

FIG. 2.

FIG. 3.

FIG. 4.

Figure 1 is a side elevation,
Figure 2 is a front elevation,
Figure 3 is a plan, and
Figure 4 is a rear perspective view of a hand-operated
water pump, showing my new design.

I claim:
The ornamental design for a hand-operated water
pump, as shown.
